(57) **CLAIM**

The ornamental design for a wound dressing, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a first embodiment of a wound dressing showing our new design; and,

FIG. 2 is a top plan view of a second embodiment of a wound dressing showing our new design.

In the drawings, dot dot dash lines are boundary lines to the disclosure and form no part of the claimed design.

The name and symbol for Avance™ displayed in the FIGS. 1 and 2 views is a trademark owned by Mölnlycke Health Care AB.

1 Claim, 2 Drawing Sheets
(1 of 2 Drawing Sheet(s) Filed in Color)
